1,970,661

AZODYESTUFF AND PROCESS OF MAKING
SAME

Leopold Laska and Arthur Zitscher, Offenbach-on-the-Main, Germany, assignors to General Aniline Works, Inc., New York, N. Y., a corporation of Delaware

No Drawing. Application August 1, 1930, Serial
No. 472,483. In Germany September 26, 1929

25 Claims. (Cl. 260—97)

Our present invention relates to new azodyestuffs and to a process of making same.

This process comprises combining any diazo-, tetrazo- or diazoazo-compound with a 3-hydroxy-diphenylamine-4-carboxylic acid-arylamide of the general formula:

wherein the benzene nucleus signified by I and the aryl-radical may be substituted, only such components being used as do not contain any group rendering the dyestuffs soluble in water and alkalies, such as the sulfonic or carboxylic acid group.

The combining components used in this process may be produced in the manner described in 20 U. S. Patent No. 1,868,612.

The new dyestuffs may be produced in substance, or on a filler in order to prepare color lakes. They are of an especial importance for the production of ice colors. They yield when 25 produced on the fiber brown shades which are of a particular value for the batic industry because of the beauty and brightness of these shades. According to the diazo-compounds used, the shades vary from the different browns to brownish black and black. The arylamides used by the present process show so great an affinity to the vegetable and animal fiber, that the goods padded therewith may be developed with diazo-compounds 30 without being previously dried.

35 In order to further illustrate our invention the following examples are given, the parts being by weight and all temperatures in centigrade degrees, but it is however to be understood, that our invention is not limited to the particular products or the reaction conditions mentioned 40 therein.

Example 1

45 Well boiled and dried cotton yarn is impregnated with a solution containing per liter 20 grs. of 3-hydroxy-diphenylamine-4-carboxylic acid anilide, 30 cc. of caustic soda solution of 34° Bé. and 20 cc. of Turkey red oil. Then it is well wrung out and developed with a solution containing sodium bicarbonate and the diazo-compound of 1.62 grs. of 3,5-dichloro-aniline per liter. Thereafter it is rinsed and soaped at the boil.

50 55 In this manner a yellowish brown dyeing is

obtained. The dyestuff thus produced on the fiber corresponds to the formula:

Example 2

Cotton yarn previously treated in the usual manner is impregnated with a solution containing per liter 20 grs. of 3-hydroxy-4'-chloro-diphenylamine-4-carboxylic acid ortho-aniside, 30 cc. of caustic soda solution of 34° Bé. and 20 cc. of Turkey red oil. After being squeezed out the yarn is developed with a diazo-solution neutralized with sodium acetate and containing per liter 1.62 grs. of 2,5-dichloro-aniline, rinsed and soaped at the boil.

In this manner a brown dyeing is obtained. The dyestuff thus produced on the fiber corresponds to the formula:

Example 3

In order to impregnate cotton with hydroxy-diphenyl-amine-carboxylic acid aryl-amides in a bath containing sodium chloride, one may work as follows:

4 grs. of the para-nitroanilide of 3-hydroxy-4'-chloro-diphenylamine-4-carboxylic acid, 10 cc. of Turkey red oil of 50% strength and 8 cc. of a caustic soda solution of 34° Bé. are made to a paste. This paste is warmed slightly and dissolved while boiling with the addition of 20 cc. of hot soft water. By the admixture of cold water the mass is made up to 1000 cc. and then mixed with 10 grs. of common salt. In this solution the material to be dyed is impregnated at 30° for 30 minutes. Then the padded and de-

100

105

110

95

hydrated material is developed by agitating it for half an hour in a diazo solution.

Example 4

- 5 Cotton yarn previously treated in the appropriate manner is impregnated in a solution containing per liter 15 grs. of the beta-naphthylamide of 3-hydroxy-diphenylamine-4-carboxylic acid, 30 cc. of caustic soda solution of 34° Bé. 10 and 10 cc. of Turkey red oil. Then the goods are well wrung out and developed in a diazo-solution neutralized with sodium-bicarbonate and corresponding per liter to 1.28 grs. of 3-chloro-aniline. Then they are rinsed and soaped 15 at the boil.

In this manner a full dark brown dyeing is obtained. The dyestuff thus produced on the fiber corresponds to the formula:

Example 5

- 30 Well boiled and dried cotton yarn is impregnated with a solution containing per liter 10 grs. of the dianiside of 3-hydroxy-diphenylamine-4-carboxylic acid, 15 cc. of caustic soda solution of 34° Bé. and 10 cc. Turkey red oil. Then it is dehydrated well and developed with the diazo solution neutralized with sodium acetate 35 and containing per liter 1.52 grs. of 5-nitro-2-amino-1-methyl-benzene. It is then rinsed and soaped at the boil. In this manner a dark brown dyeing is obtained. The dyestuff thus produced on the fiber corresponds to the formula:

- 60 When the padded goods are developed with the diazo compound of 4-nitro-2-amino-1-methyl-benzene a dyeing of yellowish brown shades is obtained.

Example 6

- 65 3 grs. of the ortho-aniside of 3-hydroxy-4'-chloro-diphenylamine-4-carboxylic acid, 4.5 cc. of caustic soda solution of 34° Bé. and 3 cc. of Turkey red oil are dissolved with the addition 70 of a usual protective agent for silk, for instance 1.5 gr. Protectol I powder double, and the whole is made up to 1 liter liquor.

Degummed spun silk is padded in this solution, 75 squeezed off and developed with the diazo-solution neutralized with sodium acetate and con-

taining per liter 1.62 grs. of 2,5-dichloro-aniline with the addition of a small amount of acetic acid. After rinsing, acidifying and hot soaping a full yellowish brown dyeing is obtained. The dyestuff thus produced on the fiber corresponds to the formula:

By starting with the para-nitranilide of 3-hydroxy - 4' - chloro - diphenylamine - 4 - carboxylic acid and with the same diazo-compound a dark yellowish brown dyeing is obtained, while with the 2,5-dichloro-aniline an olive-brown dyeing is obtained. When the diazo-compound is replaced by diazotized 4-amino-azo-benzene and the same arylamides are used, claret red shades are obtained.

Example 7

100 Viscose silk is padded with the solution containing per liter 3 grs. of the para-nitranilide of 3 - hydroxy - 4' - chloro - diphenylamine - 4 - carboxylic acid, 4.5 cc. of caustic soda solution of 34° Bé. and 3 cc. of Turkey red oil. Then the 105 material is squeezed off and developed with the diazo-solution neutralized with sodium acetate and containing per liter 2 grs. of 4-amino-azo-benzene. After working up in the usual manner a dark violet-red dyeing is obtained. The 110 dyestuff thus produced on the fiber corresponds to the formula:

115 In the same manner a claret red dyeing is obtained by replacing the para-nitranilide by the corresponding ortho-aniside.

Example 8

120 Acetate silk is impregnated with the solution containing per liter 0.5 gr. of 4-amino-azo-benzene and 1 cc. of hydrochloric acid of 20° Bé. After rinsing the material is treated in the customary manner in the bath of nitrite and hydrochloric acid. Then it is again rinsed and developed in a solution containing per liter 2 grs. of the ortho-aniside of 3-hydroxy-4'-chloro-diphenylamine-4-carboxylic acid and 2 cc. of caustic soda solution of 34° Bé. In this manner 130 a full red dyeing is obtained. The dyestuff thus produced on the fiber corresponds to the formula:

135 By replacing the ortho-aniside by the corresponding 2,5-dichloro-aniline and working otherwise in the same way a brown dyeing is obtained.

Example 9

140 Wool is impregnated with the solution containing per liter 3 grs. of the 2,5-dichloro-aniline of 150

3-hydroxy-4'-chloro - diphenylamine-4-carboxylic acid, 4.5 cc. of caustic soda solution of 34° Bé., 3 cc. of Turkey red oil and 50 grs. of common salt. The material is well squeezed and developed with 5 the diazo-solution neutralized with sodium-acetate and containing per liter 1.62 grs. of 2.5-dichloro-aniline. Thereafter it is rinsed and soaped as usual. In this manner a brown dyeing is obtained. The dyestuff thus produced on 10 the fiber corresponds to the formula:

20 The following table shows the shades of some other dyestuffs of this series:

	Diazocompound of	Combining component	Shade obtained
25	2,5-dichloroaniline	3 - hydroxy - 4'-chloro-diphenylamine-4-carboxylic-acid-ortho-isidide	Brown.
	4-chloro - 2 - amino-diphenyl-ether.	3 - hydroxy - 4'-chloro-diphenylamine-4-carboxylic-acid-orthoanisidide	Reddish brown.
30	1 - benzoylamo - 4 - amino - 2,5 - diethoxy-benzene.	3 - hydroxy - 4'-chloro-diphenylamine-4-carboxylic-acid-para-anisidide.	Do.
	2,5-dichloro-aniline	3 - hydroxy - 4'-chloro-diphenylamine-4-carboxylic-acid - para-phenemidide.	Yellowish brown.
35	2,5-dichloro-aniline	3 - hydroxy - 4'-chloro-diphenylamine - 4 - carboxylic - acid - para-phenoxanilide.	Brown.
	4 - amino - 4' - methoxy - diphenyl - amine.	3 - hydroxy - 4'-chloro-diphenyl - amine - 4 - carboxylic - acid - para-chloroanilide.	Reddish brown.
40	2,5-dichloro-aniline	3 - hydroxy - 4'-chloro-diphenyl - amine - 4 - carboxylic - acid - para-nitranilide.	Yellowish brown.
	4 - chloro - 2 - amino-diphenyl-ether.	do	Reddish brown.
	Ortho - dichloro - benzidine.	do	Dark violet brown.
45	Meta - dichloro - benzidine.	do	Reddish brown.
	2,4,5-trichloro-aniline.	do	Brown.
	3,4,5-trichloro-aniline.	do	Yellowish brown.
50	4' - nitro - 2,5 - di-methoxy - 4 - amino-azo-benzene	3 - hydroxy - 4'-chloro-diphenyl - amine - 4 - carboxylic - acid - (4 - chloro - 2 - methoxy - phenyl)-amide	Violet-black.
	2,5 - dichloro - 4 - amino-1-toluene.	3 - hydroxy - 4'-chloro-diphenyl - amine - 4 - carboxylic - acid - acenaphthyl-amide	Yellowish brown.
55	4 - chloro - 2 - amino-diphenyl-ether.	3 - hydroxy - 4'-chloro-diphenyl - amine - 4 - carboxylic - acid - 1 - an-thraquinonyl-amide.	Brown.
	2 - chloro - 4 - nitro-aniline (2 molecular proportions).	Bis - (3 - hydroxy - 4'-chloro-diphenyl - amine - 4 - carboxylic - acid - 1 - an-thraquinonyl-amide).	Deep brown.
60	4 - chloro - 2 - amino-diphenyl-ether (2 molecular proportions).	Bis - (3 - hydroxy - 4'-chloro-diphenyl - amine - 4 - carboxylic-acid - (2,5 - dichloro - phenyl) 1,3-diamide).	Yellowish brown.
	5' - nitro - 2 - amino-1-methoxy - benzene.	Bis - (3 - hydroxy - 4'-chloro-diphenyl - amine - 4 - carboxylic-acid - (2,5 - dichloro - phenyl) 1,4-diamide).	Reddish brown.
65	1 - amino - anthra - quinone.	3 - hydroxy - 4'-methyl-diphenyl - amine - 4 - carboxylic - acid - ortho-anisidide.	Full reddish brown.
	2,4,5-trichloro-aniline.	3 - hydroxy - 2' - methyl-diphenyl - amine - 4 - carboxylic - acid - beta-naphthalide.	Yellowish brown.
70	2,5-dichloro-aniline	3 - hydroxy - 3' - methyl-diphenylamine-4-carboxylic-acid-beta-naphthalide.	Do.
	5-nitro-2-amino-1-toluene.	3 - hydroxy - 2' - methoxy-diphenylamine-4-carboxylic-acid-anilide.	Reddish brown.
75			

Diazocompound of	Combining component	Shade obtained
4-amino-3,2'-dimethyl-azo-benzene.	3-hydroxy-4'-methoxy-diphenylamine-4-carboxylic-acid-anilide.	Full blackish red. 80
2-nitro-aniline	3-hydroxy-4'-phenoxy-diphenylamine-4-carboxylic-acid-para-nitro-anilide.	Yellowish brown.
4'-nitro-2,5-dimethoxy-4-amino-azo-benzene.	3-hydroxy-2'-dichloro-diphenylamine-4-carboxylic-acid-para-nitro-anilide.	Black.
4-amino-3,2'-dimethyl-azo-benzene.	3-hydroxy-2'-methyl-5'-chloro-diphenylamine-4-carboxylic-acid-para-nitro-anilide.	Reddish brown. 85
1-benzoylamo - 4 - amino - 2,5 - diethoxy-benzene.	3-hydroxy-3' - methyl-4'-chloro-diphenyl - amine - 4 - carboxylic - acid - (5 - chloro - 2 - methoxy - phenyl)-amide.	Violet-brown.
1-amino-anthraquinone.	3-hydroxy-3' - methyl-4'-methoxy - diphenylamine-4-carboxylic-acid-para-nitro-anilide.	Brown. 90

Since an object of the present invention is to provide dyestuffs of good fastness properties, which dyestuffs are insoluble in water and alkalies, it is to be understood that the aromatic nuclei of the general formulæ appearing in the appended claims do not contain any substituents which are known to render organic compounds soluble in water or alkalies and to tend to depreciate the fastness of the dyestuffs to alkalies. Substituents of this kind are, for instance, the sulfonic acid and the carboxylic acid group. 95

The structural formulæ given for our new azo-dyestuffs are correct to the best of our knowledge and belief. However, it has not yet been possible to definitely determine the exact structure of these new azo-dyestuffs. For example, it is conceivable that the azo group is attached to the phenyl nucleus II in ortho-position to the hydroxyl group instead of in para-position as indicated in the structural formulæ given. Consequently we wish it understood that when such structural formulæ are employed in the appended claims, they are intended to define the new azo-dyestuffs which we have described and which may be obtained in accordance with our disclosure. 105

We claim:

1. Process which comprises combining an aromatic diazo compound of the benzene or anthraquinone series, with a 3-hydroxy-diphenylamine-4-carboxylic-acid-aryl-amide of the formula:

wherein R stands for a radical of a mono-nuclear or polynuclear isocyclic aromatic compound and wherein the benzene nucleus signified by I may be substituted by alkyl, alkoxy, aryloxy or halogen. 125

2. Process which comprises combining an aromatic diazo compound of the benzene series which may be substituted by alkyl, alkoxy, aryloxy, acylamino, arylamino, nitro groups or halogen atoms, or a further diazo or an azo group, with a 3-hydroxy-diphenylamine-4-carboxylic-acid-aryl-amide of the formula:

wherein the benzene nucleus I may be substituted by alkyl, alkoxy, aryloxy or halogen and the benzene nucleus III may be substituted by nitro, alkyl, alkoxy, aryloxy or halogen. 135

3. Process which comprises combining an aromatic diazo compound of the benzene series which

may be substituted by alkyl, alkoxy, aryloxy, halogen or nitro, with a 3-hydroxy-diphenylamine-4-carboxylic acid arylamide of the formula:

10 wherein X stands for alkyl, alkoxy or halogen and the benzene nucleus III may be substituted by alkyl, alkoxy, aryloxy, halogen or nitro.

15 4. Process which comprises combining an aromatic diazo compound of the benzene series which may be substituted by alkyl, alkoxy, aryloxy, halogen or nitro, with a 4'-chloro-3-hydroxy-diphenylamine-4-carboxylic acid arylamide of the formula:

wherein the benzene nucleus III may be substituted by alkyl, alkoxy, aryloxy, halogen or nitro.

25 5. Process which comprises combining an aromatic diazo-compound of the benzene series which may contain alkyl, alkoxy, aryloxy or nitro-groups or halogen-atoms, with a 4'-chloro-3-hydroxy-diphenyl-amine - 4 - carboxylic acid-nitranilide of the formula:

35 6. Process which comprises combining an aromatic diazo-compound of the benzene series which may contain alkyl, alkoxy, aryloxy or nitro-groups or halogen-atoms, with a 4'-chloro-3-hydroxy - diphenyl - amine - 4 - carboxylic - acid-para-nitranilide of the formula:

45 7. Process which comprises combining the diazocompound of 2,5-dichloro-aniline with 4'-chloro-3-hydroxy-diphenyl - amine-4-carboxylic-acid-para-nitranilide of the formula:

55 8. The azo dyestuffs which are obtainable by combining an aromatic diazo compound of the benzene or anthraquinone series with a 3-hydroxy- diphenylamine - 4 - carboxylic - acid-aryl- amide of the formula:

65 wherein R stands for a radical of a mononuclear or polynuclear isocyclic aromatic compound, and wherein the benzene nucleus signified by I may be substituted by alkyl, alkoxy, aryloxy or halogen.

69. The azo dyestuffs of the general formula:

75 wherein the benzene nucleus I may be substituted by alkyl, alkoxy, aryloxy or halogen, the benzene nucleus III may be substituted by nitro, alkyl,

alkoxy, aryloxy or halogen, and the benzene nucleus IV may be substituted by alkyl, alkoxy, aryloxy, acylamino, arylamino, nitro groups or halogen atoms or a further diazo or an azo group.

10. The azo-dyestuffs of the general formula: 80

85

wherein X means alkyl, alkoxy or halogen and the nuclei III and IV may be substituted by alkyl, alkoxy, aryloxy, halogen or nitro, which compounds yield when produced on a substratum brown shades. 90

11. The azo-dyestuffs of the general formula:

95

wherein the nuclei III and IV may be substituted by alkyl, alkoxy, aryloxy, halogen or nitro, which compounds yield when produced on a substratum brown shades. 100

12. The azo-dyestuffs of the general formula:

105

wherein the nucleus IV may be substituted by alkyl, alkoxy, aryloxy, halogen or nitro, which compounds yield when produced on a substratum brown shades.

13. The azo-dyestuffs of the general formula: 115

110

wherein the nucleus IV may be substituted by alkyl, alkoxy, aryloxy, halogen or nitro, which compounds yield when produced on a substratum brown shades. 125

14. The azo-dyestuff of the formula:

135

which compound yields when produced on a substratum yellowish brown shades.

15. The azo-dyestuff of the formula:

140

which compound yields when produced on a substratum brown shades. 145

16. The azo-dyestuff of the formula:

15 which compound yields when produced on a substratum full reddish-brown shades.

17. Fiber dyed by means of the azodyestuffs claimed in claim 8.

18. Fiber dyed by means of the azodyestuffs claimed in claim 9.

19. Fiber dyed by means of the azodyestuffs claimed in claim 10.

20. Fiber dyed by means of the azodyestuffs claimed in claim 11.

21. Fiber dyed by means of the azodyestuffs claimed in claim 12.

22. Fiber dyed by means of the azodyestuffs claimed in claim 13.

23. Fiber dyed by means of the azodyestuff claimed in claim 14.

24. Fiber dyed by means of the azodyestuff claimed in claim 15.

25. Fiber dyed by means of the azodyestuff claimed in claim 16.
